(57) **CLAIM**

The ornamental design for a plumbing tool, as shown and described.

DESCRIPTION

FIG. 1 is a top front perspective view of a first embodiment of a plumbing tool showing the new design.

FIG. 2 is a front view of the plumbing tool of FIG. 1.

FIG. 3 is a first side view of the plumbing tool of FIG. 1.

FIG. 4 is a second side view of the plumbing tool of FIG. 1.

FIG. 5 is a top view of the plumbing tool of FIG. 1.

FIG. 6 is a bottom view of the plumbing tool of FIG. 1.

FIG. 7 is a rear view of the plumbing tool of FIG. 1.

FIG. 8 is a front perspective view of the plumbing tool of FIG. 1 with an optional cart.

FIG. 9 is a top front perspective view of the second embodiment of a plumbing tool showing the new design.

FIG. 10 is a front view of the plumbing tool of FIG. 9.

FIG. 11 is a first side view of the plumbing tool of FIG. 9.

FIG. 12 is a second side view of the plumbing tool of FIG. 9.

FIG. 13 is a top view of the plumbing tool of FIG. 9.

FIG. 14 is a bottom view of the plumbing tool of FIG. 9.

FIG. 15 is a rear view of the plumbing tool of FIG. 9; and,

FIG. 16 is a front perspective view of the plumbing tool of FIG. 9 with an optional cart.

The broken lines shown in the figures are for the purpose of illustrating portions of the plumbing tool and form no part of the claimed design. The broken lines showing of the cart in FIGS. 8 and 16 are for the purpose of illustrating environmental structure and form no part of the claimed design.

1 Claim, 16 Drawing Sheets
